UNITED STATES PATENT OFFICE.

JABEZ LONES, CHARLES VERNON, AND EDWARD HOLDEN, OF SMETHWICK,
ENGLAND.

WHEEL-TIRE.

SPECIFICATION forming part of Letters Patent No. 515,596, dated February 27, 1894.

Application filed May 11, 1893. Serial No. 473,757. (No model.)

To all whom it may concern:

Be it known that we, JABEZ LONES, CHARLES VERNON, and EDWARD HOLDEN, all of Smethwick, England, subjects of the Queen of Great Britain, have invented certain new and useful Improvements in the Tires of the Wheels of Wagons and Carriages and other Road-Vehicles; and we do hereby declare that the following is a full, clear, and exact description of the invention, which will enable others skilled in the art to which it appertains to make and use the same.

Our invention has reference to the iron or steel tires of wheels having wooden felloes the said tires being shrunk upon the felloes and our said invention consists of the several improvements hereinafter described for fixing the tires to the felloes without nails, bolts or other like fastenings.

20 In making a tire according to our invention we roll the iron or steel bar from which it is to be made, flat on its outer face and concave on its inner face, the outer edge being rounded and the inner edge being flat or square; or 25 we roll the outer face convex and the inner face concave and we also roll on the inner face of either of the bars described a series of conical, hemispherical or other shaped projections, or a series of knife edged ribs for 30 fixing the tire to the felly without nails, bolts or other like fastenings; that is to say, the said projections or knife edged ribs on the shrinking of the tire on the felloes penetrate the wood of the felloes and thereby fix the 35 tire securely in its place. The projections may be grouped or variously arranged on the inner face of the tire and various kinds of knife edged ribs may be used; for example, a series of inclined and equi-distant ribs may 40 be used, or a series of ribs may be made to cross one another so as to form a lozenge shaped pattern on the inner face of the tire; or ribs arranged in the directions of diagonals to the sides of the tire, or a rib having 45 an undulating or wave like form may be used.

The projections or ribs for securing the tires to the felloes may be used with tires having the sectional figures described or with tires having the following sectional figure. We make both 50 the faces of the tire flat and give it a slightly

taper figure in cross section, that is, the tire at its inner edge is slightly thicker than at its outer edge and we make along each of the edges of the tire an inwardly projecting lip or flange which lips or flanges on the shrinking 55 of the tire close or contract upon the edges of the felloes and thereby assist in fixing the tire to the felloes. We make the lip at the outer edge of the tire much stronger than that at the inner edge, the said strong lip 60 serving to protect the outer edges of the felloes. The edge of the outer lip or flange may be straight or slightly undercut.

Figures 1 to 16 of the accompanying drawings represent portions of wheel tires made 65 according to our invention having different sectional figures and provided with different kinds of projections or ribs on their inner faces for fixing the tires to the wooden felloes without nails, bolts or other fastenings. 70

Fig. 1 represents in cross section and Fig. 2 in inner elevation a portion of a tire made of a rolled iron or steel bar flat on its outer face and concave on its inner face, the outer edge being rounded and the inner edge being 75 flat or square. On the inner face of the bar a series of separated knife edged or nearly knife edged ribs *a, a, a* is rolled. We prefer to arrange the knife edged ribs *a, a, a* on the inner concave face of the bar in the manner 80 represented but they may be variously arranged. We prefer to roll the separated ribs *a, a, a* on the bar in the following manner. By the rolling operation by which the figure of the bar is perfected, we roll upon its inner 85 face continuous ribs of the sectional figure represented and by a subsequent rolling operation we roll out into the substance of the bar portions of the ribs so as to leave the separated or detached ribs *a, a, a* represented 90 in the drawings.

Fig. 3 represents in side elevation and Fig. 4 in cross section a portion of a tire of the kind represented in Figs. 1 and 2 attached to the wooden felly *b* of the wheel by the knife 95 edged ribs *a, a* on the inner face of the tire penetrating on the shrinking of the tire into the wood of the felloes and thereby preventing any lateral motion of the tire upon the felloes. The tire is thereby fixed to the fel- 100

lies without nails, bolts or other like fastenings, the concave face of the tire assisting in securing it in its place.

It will be seen by an examination of Fig. 4 5 that when the tire is fixed to the fellies the rounded edge *c* projects beyond the fellies and prevents the fellies being injured by coming into contact with the curb-stones or other objects.

10 Fig. 5 represents in cross section and Fig. 6 in inner elevation, a portion of a tire provided on its inner face with a series of inclined and equi-distant knife-edged ribs marked *d*, *d*, *d* for the same purpose as the ribs *a*, *a*, *a* the 15 projecting curved edge *e* of the tire having a somewhat different shape from that represented in Fig. 1.

Fig. 7 represents in cross section and Fig. 8 in inner elevation a portion of another tire 20 made according to our invention. The bar from which this tire is made is concave on its inner face and convex on its outer face, and has a curved projecting edge. The inner face of the bar has made on it by the 25 rolling operation a series of crossing knife edged ribs marked *f*, *f*, *f* so as to form a lozenge shaped pattern on the inner face of the tire for locking it to the wooden fellies. Or knife edged ribs arranged in the directions 30 of diagonals to the sides of the tire may be employed as represented in cross section in Fig. 9 and inner elevation in Fig. 10, the diagonal rib being marked *g*. Or a knife edged rib having an undulating or wave like figure 35 marked *h* represented in cross section in Fig. 11 and inner elevation in Fig. 12 may be used for the same purpose.

Although we prefer when using projections or ribs to give them the form in cross section 40 of knife edges, as described and represented yet the projections or ribs may have other figures given to them which on the shrinking of the tire will grip or bind the tire to the fellies. For example, a series of conical projections 45 may be rolled on the inner face of the bar as represented in cross section in Fig. 13 and inner elevation in Fig. 14 and marked *k*; or a series of hemispherical projections marked *l*, *l* as represented in Figs. 15 and 16 50 may be employed. The tire bar Figs. 13 and 14 is flat on its inner face and convex on its outer face, and the tire bar Figs. 15 and 16 is flat on both faces.

In Figs. 11 and 12 we have represented a 55 tire having an inwardly projecting rib or flange rolled along each edge. These lips or flanges, marked respectively *m* and *n*, on the shrinking of the tire close or contract upon the edges of the fellies and thereby assist in 60 fixing the tire to the fellies. The lip *n* at the

outer edge of the tire is made much stronger than the lip *m* at the inner edge of the tire, the strong lip *n* serving to protect the outer edge of the fellies. The other lip *m* may either be straight as represented or slightly undercut. Both faces of this tire bar are flat, the bar being slightly taper in cross section, that is to say, the edge near the lip or flange *m* is slightly thicker than the edge near the strong flange or lip *n*.

Having now particularly described and ascertained the nature of our invention and in what manner the same is to be performed, we claim as our invention—

1. In tires for the wheels of wagons and carriages and other road vehicles, the combination with projections or ribs on the inner faces of the said tires for locking the tires to the wooden fellies of the wheels, of a rounded edge on the outer sides of the tires projecting 80 beyond the fellies of the wheels for protecting the said fellies from injury by coming into contact with curb stones or other obstacles, substantially as herein set-forth and shown.

2. A wheel tire provided on its inner face with one or more ribs extended diagonally to the sides of the tire for locking the said tire to the felly of a wheel, substantially as herein set forth and shown.

3. A wheel tire provided on its inner face with a series of crossing knife edge ribs for locking the said tire to the wooden fellies of wheels, substantially as herein set-forth and shown.

4. A wheel tire provided on its inner face with a knife edge rib in the form of a diagonal to the sides of the tire for locking the said tire to the fellies of wheels, substantially as herein set-forth and shown.

5. The method of forming a metal wheel tire having its inner face provided with a series of short separated ribs or locking projections, which consists in rolling a continuous rib upon the inner face of a metal bar 105 during the rolling operation in which the figure of said bar is perfected, subsequently rolling out portions of said continuous rib into the substance of the tire-bar so as to leave thereon a series of separated or detached ribs, and finally bending the said bar into the form of a wheel tire, substantially as described.
